(57) **CLAIM**

The ornamental design for a connector receptacle cage, as shown.

DESCRIPTION

FIG. 1 is a top, front and right side perspective view of a connector receptacle cage showing my new design;

FIG. 2 is a top plan view thereof;

FIG. 3 is a front elevation view thereof;

FIG. 4 is a rear elevation view thereof;

FIG. 5 is a right side elevation view thereof;

FIG. 6 is a left side elevation view thereof; and,

FIG. 7 is a bottom plan view thereof.

The broken line in the drawing views is included to illustrate environment only and forms no part of the claimed design.
